D15-67. OR D17,905 EX

DESIGN.

—o—
N. WHEELER.

SEWING MACHINE CABINET.

No. 17,905.

Patented Nov. 22, 1887.

UNITED STATES PATENT OFFICE.

NATHANIEL WHEELER, OF BRIDGEPORT, CONNECTICUT.

DESIGN FOR A SEWING-MACHINE CABINET.

SPECIFICATION forming part of Design No. 17,905, dated November 22, 1887.

Application filed August 11, 1887. Serial No. 246,740. Term of patent 14 years.

To all whom it may concern:

Be it known that I, NATHANIEL WHEELER, a citizen of the United States, residing at Bridgeport, in the county of Fairfield and State of Connecticut, have invented and produced a new and original Design for Sewing Machine Cabinets; and I do declare the following to be a full, clear, and exact description of the same, reference being had to the accompanying drawing, which is a perspective of a sewing-machine cabinet made in conformity with my novel design, the cover being in place and the extension leaf in the folded position.

15 The leading features of my design consist in the peculiar configuration of the outer supports or frame-work for the drawers, the inner edge portions of the triangular brackets beneath the table, and the ornamentation of 20 the cover, these several parts being of general harmonious ornamental conformation.

1 denotes the table, the edges of which are fluted or ribbed, and 2 the extension-leaf, having similar edges. The outer frame-work of 25 the supports for the drawers 3 consists of the rounded vertical posts 8, having groups of beads 10 and squared portions 11, faced with circular buttons 12, said posts terminating at their lower ends in rounded knobs 13. About 30 the middle of the posts 8 are horizontal fluted or ribbed cross-bars 7; and the bottom pieces, 6, of the drawer supports are also fluted or ribbed at their edges.

Beneath the front edge of the table and 35 against the inner casings, 5, of the drawer-supports are the triangular brackets 9, the edge pieces, 14, of which are rounded in their central portions and ornamented with beads 15, the end portions, 16, of the said edge pieces 40 being square. The cover 4 has rounded corner-posts 17, ornamented with groups of beads 18. The upper slanting portions of the said cover are partly fluted or ribbed at 19, and around the panels of the sides and ends

of the cover are fluted or ribbed borders 20. 45 It will thus be apparent that there is a general harmony of design between the rounded and beaded posts 8, edge pieces, 14, and corner-posts 17, and also between the fluted or ribbed edges of the table and extension-leaf, 50 the fluted cross bars 7, bottom pieces, 6, and the fluted or ribbed ornamentation of the cover. Moreover, there is a certain pleasing harmony of appearance between the beads or ribs on the posts 8 and 17 and edge pieces, 14, and the 55 fluted or ribbed ornamentation of the other parts.

I claim—

1. The design for a sewing-machine cabinet, consisting of the rounded vertical posts 8, or- 60 namented with groups of beads or ribs 10, and having squared portions 11, with circular buttons, as shown and described.

2. The design for a sewing-machine cabinet, consisting of the triangular brackets 9, bav- 65 ing rounded edge pieces, 14, ornamented with groups of beads 15, as shown and described.

3. The design for a sewing-machine cabinet, consisting of the cover 4, having rounded corner-posts 17, ornamented with groups of beads 70 18, as shown and described.

4. The design for a sewing-machine cabinet, consisting of the cover with the fluted or ribbed ornamentation and the rounded corner-posts with groups of beads, the table and extension-leaf with fluted or ribbed edges, the triangular brackets 9, having rounded edge pieces 75 with groups of beads, and the drawer-sup- ports comprising the rounded vertical posts 8, with groups of beads, and the fluted or 80 ribbed cross-bars 7 and bottom pieces, 6, as shown and described.

In testimony whereof I affix my signature in presence of two witnesses.

NATHANIEL WHEELER.
